UNITED STATES PATENT OFFICE.

JOHN E. FITZGERALD, OF PROVIDENCE, RHODE ISLAND.

FINGER-RING.

No. 901,333.

Specification of Letters Patent.

Patented Oct. 20, 1908.

Application filed May 2, 1908. Serial No. 430,573.

To all whom it may concern:

Be it known that I, JOHN E. FITZGERALD, a citizen of the United States, residing at Providence, in the county of Providence and State of Rhode Island, have invented certain new and useful Improvements in Finger-Rings, of which the following is a specification, reference being had therein to the accompanying drawings.

10 Like reference numerals indicate like parts.

Figure 1 is an elevation of a finger ring provided with my improvement hereinafter described. Fig. 2 is a top view of said finger ring with my improved signet plate secured therein. Fig. 3 is a plan view of the detachable signet plate as seen on the reverse side thereof. Fig. 4 is an edge view of said signet plate. Fig. 5 is a side elevation of one of the resilient locking bars used to hold the signet plate in wearing position, and shows its outwardly directed surface. Fig. 6 is a top plan view of one of said locking bars. Fig. 7 is a side elevation of said locking bar, showing its inwardly directed surface. Fig. 8 is a top plan view of the two locking bars placed in contact in their operative position. Fig. 9 is a view of the interior of the box or head of the finger ring. Fig. 10 is a sectional view of said box or head as seen on line *z z* of Fig. 9. Fig. 11 is a top plan view of one of the blocks for securing the locking bars at the end thereof. Fig. 12 is a sectional view of said block as seen on line *w w* of Fig. 11. Fig. 13 is a top plan view of a rivet plate used in connection with the block which is shown in Fig. 11. Fig. 14 is a view on an enlarged scale of the box or head and all the parts assembled therein, which constitute my invention, as seen partly in elevation and partly in section on line *z z* of Fig. 9.

My invention relates to that class of finger rings provided with a box or head in which a signet plate is detachably mounted; and it consists of the novel construction and combination of the several parts as hereinafter described and claimed.

In the drawings the finger ring is designated by the reference numeral 1 and may be of any desired form and style. The finger ring has a box or head 2, which may be oval, square, or of any preferred shape. The box or head 2 preferably has the annular or external surrounding flange or bezel 3, whose outer edge lies in one plane throughout its entire extent. The inner surface of the

flange or bezel 3 tapers conically, as shown in Figs. 10 and 14. An integral ledge or annular seat 4 extends inwardly all around the box or head 2, adjacent to the base of the flange or bezel 3. A hole or aperture 5 is made centrally through the bottom of the box or head 2.

Two blocks 6 and 7 are soldered or otherwise secured within the box or head 2, as best represented in Fig. 9, and separately illustrated in Figs. 11 and 12. Each of said blocks has a slot 8 (or 9), whose inner end is closed and whose sides diverge outwardly. The block 7 is not so high as the block 6 and is provided near its end with two integral studs 10, which extend up from its upper surface. The slots 8 and 9 of the blocks 6 and 7 are opposite each other and extend in the line of the major diameter of the box or head 2. The block 6 extends up nearer to the ledge 4 than the block 7 does, so that the slot 8 has a closed top and rear end, whereas the slot 9 has a closed rear end, but an open top.

There are two locking bars 11 and 12, each made of tempered metal having a good degree of resilience. Each locking bar has a central semi-circular portion or bow-shaped bend 13 (or 14) projecting from its outer side, and a concentric semi-circular concavity or socket 15 of less diameter than the projecting portion 13 (or 14) of said bar. Each bar is, at and as far as said projections, rectangular in cross section, and has its inner surface 16 straight. The two locking bars 11 and 12 are placed together with their respective inner surfaces 16 in contact, as illustrated in Fig. 8, and then the two concavities 15 form a circular hole or opening as seen at 15^a. The inner portion of the bow or bend 13 of each locking bar is concentrically beveled, or made with a conical taper, as seen at 17. There is such a tapering both on the upper portion and the lower portion of each locking bar, the latter forming a conical concavity designated as 17^a in Fig. 7, and this leaves a sharp annular ridge, or central circumferential enlargement, as indicated by 18 in said figure.

The locking bars 11 and 12 when placed together, as in Fig. 8, are seated at their ends in the slots 8 and 9, respectively, and so are prevented from longitudinal movement in the box or head 2, although by the outwardly tapering shape of the slots 8 and 9 said bars have room for a slight lateral

movement. The slots 8 and 9, however, at their inner or closed ends, are equal in width to the width of the bars 11 and 12, when they are in the position shown in Fig. 8, so that 5 said bars at their extreme ends, when so in engagement in said slots, have no lateral play whatever.

A rivet plate 19 has two rivet holes 20 so placed and of such size as to allow the studs 10 of the block 7 to pass loosely through said holes. The ends of the studs 10 are then hammered down to form rivet heads 21, as represented in Fig. 14. Thus the locking bars 11, 12, are secured in position and can 15 not be accidentally removed or lifted out of engagement.

The signet plate is represented at 22 and is of a shape to fit exactly within the flange or bezel 3 of the box or head 2 in frictional 20 contact therewith, the edge of the signet plate 22 being suitably beveled for that purpose, as shown at 23. The annular portion of the outer surface of the signet plate 22 lies flush, or in the same plane with the outer 25 surface of the flange or bezel 3 of the box or head 2, as illustrated in Figs. 2 and 14. The outer surface of the signet plate has an emblem 24, or initial, or other design, formed thereon by engraving, or in relief, or otherwise. It gives a more finished appearance if the signet plate has a plain annular border 30 25, as illustrated in Fig. 2.

At the center of the signet plate 22 on the back thereof is a cylindrical post 26, and on 35 the end of said post a knob or spherical head 27. The post 26 and knob 27 together are of such a length that the knob or ball 20 extends to the hole 5 of the box or head 2, when the signet plate 22 is seated in the box or head 40 45 with its outer rim flush with the outer edge of the flange or bezel 3. The outer end of the ball or knob 26 is squared off so as not to project through the hole 5 in the bottom of the box or head 2.

50 In assembling the signet plate 22 with the other parts of the device, the ball or knob 27 of the post 26 of the signet plate is first seated in the circular concavity 15^a at the center of the locking bars 11 and 12 on their upper side, and thus is accurately centered. Pressure is then applied to the outer surface of the signet plate, whereupon the ball or knob 27 spreads apart the locking bars 11 and 12 until it passes down into the concavity 17^a on the lower portion of said bars. The annular ridge 18 then shuts or snaps snugly against the post 25 and over the ball or knob 27, and prevents the ball or knob from rising therefrom out of engagement. 55 The signet plate 22 is thus securely locked in wearing position. To disengage the signet plate from the box or head 2 of the finger ring, a metallic rod or pin is pressed against the end of the ball 27 through the opening 5 of the bottom of the box or head 2. Such

inward pressure causes the ball or knob 27 to spread apart the locking bars 11 and 12 and so the ball or knob is moved past or away from the constriction of the annular ridge 18 of said locking bars, whereupon the signet plate 22 is detached from the box or head. The same signet plate can be replaced in wearing position whenever desired, or another signet plate, having some other emblem, initial, or design, can be substituted 75 therefor.

I claim as a novel and useful invention and desire to secure by Letters Patent:

1. In a finger ring, the combination of a box or head; a signet plate having a central 80 post with a ball at the extremity of said post; and two resilient locking bars extending in contact and parallel with each other, having central semi-circular locking seats, respectively, which register with each other, 85 through which registering locking seats said ball is movable by pressure applied to the signet plate to confine said signet plate in a position flush with the outer rim of said box or head.

2. In a finger ring, the combination of a box having a bezel; a signet plate engageable with said bezel; a post extending centrally from the signet plate; a ball fastened on the end of the post; and two resilient 95 locking bars mounted at their ends in the box parallel with each other, each having a central semi-circular bow, beveled on its inner edge, and together forming, when in registration, a central circular locking aperture 100 provided with conically directed inner edges which are adapted to engage said ball and post.

3. In a finger ring, the combination of a box; a signet plate adapted to cover said box 105 at its outer end; two blocks secured at the opposite sides of said box and each having a slot; two parallel, resilient locking bars mounted at their ends in said slots, respectively; and a post on the signet plate terminating with a ball, which locking bars are provided with locking means for the engagement of said post and ball between them.

4. In a finger ring, the combination of a box; a signet plate; a post on the signet 115 plate terminating with a ball; two blocks secured within the box at one end and each provided with a slot, one of said blocks having the upper side of its slot closed; which slots are in alignment with each other; two 120 studs on the top of the other of said blocks; a rivet plate having two rivet holes with which said studs respectively register; two parallel, resilient locking bars, secured in the box by the engagement of their ends with 125 said slots, respectively; and locking devices on said bars adapted to engage the post and ball of the signet plate.

5. In a finger ring, the combination of a box; two parallel resilient locking bars se- 130

cured at their ends within the box and each having a locking device comprising a central semi-circular portion with a beveled or tapering concentric semi-circular seat on its 5 upper side and also with a beveled or tapering concentric semi-circular seat on its lower side, which seats are axially in alinement, in communication with each other, and together constituting a circular locking device 10 having an intermediate concentric annular

ridge; a signet plate; a post on said plate; and a ball on the post movable through said seats and held in position by the engagement of said post with said locking devices.

In testimony whereof I affix my signature 15 in presence of two witnesses.

JOHN E. FITZGERALD.
